UNITED STATES PATENT OFFICE.

CLARENCE M. KEMP AND ARTHUR BIXBY, OF BALTIMORE, MARYLAND;
SAID BIXBY ASSIGNOR TO SAID KEMP.

VOTING-MACHINE AND TOY BANK.

SPECIFICATION forming part of Letters Patent No. 439,406, dated October 28, 1890.

Application filed November 7, 1889. Serial No. 329,710. (No model.)

To all whom it may concern:

Be it known that we, CLARENCE M. KEMP and ARTHUR BIXBY, citizens of the United States, residing at Baltimore, in the State of Maryland, have invented certain new and useful Improvements in a Combined Voting-Machine and Toy Bank, of which the following is a specification, reference being had therein to the accompanying drawings.

10 Our invention relates to the improvements in a combined voting-machine and toy bank, wherein the money put into the bank is made to operate mechanism for recording the number of deposits and also to bring into view or 15 prominence certain figures and to depress or remove from view other figures at the same time. The mechanism on which the coin drops will give the coin no inclination to operate in favor of one figure or the other, but 20 leave it to chance which figure shall appear prominent.

The invention also gives means of making a decided vote for any of the figures by shifting the deposit-opening to one side or the 25 other or placing other deposit-openings on each side of the main deposit-opening.

Figure 1 is a view of the apparatus with a large portion of the front of the outside casting removed. Fig. 2 is a side view of cylinder B and the deposit-opening A, showing the coin dropping from the latter to the former. Figs. 3 and 4 are side and front views of one 30 of the recording-wheels and the lever carrying the pawl to move same. Figs. 5 and 6 are perspective and side views of the trough through which the coin passes into the partitioned box or safe. Fig. 7 is a view from the front, showing the manner in which the figures are disclosed and secreted.

40 A is the slot or hole into which the coin is placed. On the inside of this slot is a tube a, having a bend extending over and a short distance removed from a flanged cylinder B, operating on a pivot b, and made very 45 light and capable of movement by very small force. b' represents the curved surface on which the coin is dropped from the end of tube a. The central line of tube a is a vertical continuation of the diameter-line of the 50 cylinder B. Hence the coin when dropped is left to its own inclination as to its move-

ment to the right or left. Upon striking the surface b' it rebounds, then passes downward either to the right or left, and strikes one of the wings or projections b² or b³, upon which 55 it will press by means of its fall and weight, and thus give the cylinder movement on its axis in the direction of the coin's fall. A pin b⁵ in the cut-away portion b⁴ of one of the cylinder-heads limits the movement of the 60 cylinder after moving the cylinder B. The coin drops from the wing b² or b³. For easier description we will say the coin drops from wing b³ against the lever C, pivoted at c and having at its opposite end a pawl c', engaging 65 teeth of ratchet-wheel E.

Ratchet-wheel E has upon its front face numbered divisions, which divisions passing when wheel E is revolved before an opening in the outer case exhibits the record of the 70 number of times pawl c' on the lever C has been actuated by coins dropping against the latter, and consequently is a record of the number of times lever C has been actuated in this one direction. g is a stop-pin to prevent lever C going farther than enough to actuate the ratchet-wheel to the extent of one tooth through pawl c'. G is a trough into which the coin next passes. This narrows and provides another vertical opening for the 80 coin to drop through onto the cylinder H beneath it. Cylinder H—likewise cylinder L—is similar to cylinder B in construction and performance. Troughs K K and O O are similar in construction and performance to trough 85 G. Ratchet-wheels F, J, I, N, and M are also similar in construction and performance to ratchet-wheel E. Likewise the levers and pawls D and d', h and h', e and e', n and n', and m and m' are in character and performance the 90 same as C and c', and the pins g' h' e' n' m' are for similar purposes as the pin g. P and P' is the bottom, where the coin finally settles. The bottom of the last trough terminates over the partitioned box or safe, and some of the 95 coins by chance will drop to one side into P and some of the coins into P'. One of these boxes, as P, is left open, so that whatever coins may drop into it can be withdrawn. Thus any one putting a coin in has a chance to see the 100 working of the apparatus free of cost by the coin returning to said box P, and all coins

dropping into P' remain in the same, which will be considered the bank.

On the front heads of each of the cylinders B, H, and L are supposed to be shown four faces, two representing the countenances of one candidate, one of the countenances R' expressing agony and the other R expressing bliss, the other figures representing agonized and blissful countenances S' S of the other candidate. There are three holes T t' t" in the front casing of the apparatus, opposite each cylinder, arranged so that when the coin has moved the cylinder to the right the blissful face S of one candidate presents itself at one opening T and the agonized countenance R' of the opposing candidate shows at another opening t, while the third opening t" shows blank or some different figure, if desired; but if the coin has moved the cylinder to the left the 20 blissful face R appears at t" and the agonized face S' of the other candidate appears at t, and the other faces S and R' are concealed. Each cylinder B, H, and L can be arranged with the faces of the same or other candidates 25 or figures of any kind to please the fancy. By heightening the apparatus more cylinders can be placed in the apparatus and more ratchet-wheels, whereby an extensive combination of faces or characters can be brought into play 30 and recorded by means of the fall and weight of one coin. Only one cylinder and two ratchet-wheels need be used, if desired, or any other proportionate number of cylinders and ratchets can be used in which the trough O O will receive the coin from the only cylinder or from 35 the last cylinder, according to whether one or several be used. If the person dropping the coin in wants it to record for a specific candidate, the extra openings a² and a³ are so placed 40 that the coins leaving a² drop to the left-hand side (of the vertical line passing through the center of the cylinder) onto the cylinder B. Likewise coins passed through a³ drop to the 45 right-hand side of the vertical line onto the cylinder B, thus making a positive record for the selected candidate. The cylinders need not have the curved surface b' extended farther than the wings b² and b³, and the mechanism for recording can be differently operated by the coin instead of the specific mechanism shown, and instead of faces showing 50 on the front heads of the cylinders other devices can show or be operated by the cylinders. The apparatus can be used without 55 the recording devices, if desired.

The apparatus can be operated by other bodies, as marbles, by making the slotted opening to suit same; but it is preferably made for coin. The coin will produce the same result if a wire or narrow plate be set beneath it, off which it can fall to one side or the other, which will answer the same purpose as the curved portion of the cylinder, in which case a lever fulcrumed in the middle would answer 60 the purpose of wings b² and b³.

The coins will operate the mechanism or

cylinders B, H, and L without the use of the recording-wheels and their actuating-levers and pawls.

What we claim as our invention is—

7c

1. In a coin-operated mechanism, an oscillatory cylinder for receiving actuation from the fall and weight of a coin, in combination with a coin-chute placed above the cylinder, through which chute the coin is dropped upon 75 said cylinder, and according to the direction the coin may perchance fall the cylinder is oscillated in the direction as chance may determine.

2. In a coin-operated mechanism, an oscillatory cylinder, in combination with two coin-chutes placed above on opposite sides of the center of the cylinder, whereby the cylinder may be operated in either one of its two directions at the will of the operator by dropping a coin in the selected chute.

3. In a coin-operated mechanism, an oscillatory cylinder provided with figures or characters, whereby when motion is given by the fall and weight of a coin upon said cylinder 90 the figures are likewise moved.

4. In a coin-operated mechanism, an oscillatory cylinder and a coin-chute above it, in combination with recording devices for recording the direction of the movement of said 95 cylinder.

5. In a coin-operated mechanism wherein the movements are made by the fall and weight of a coin, two or more oscillatory cylinders, in combination with a chute and one 100 or more troughs, each of which is placed above one of the cylinders and each trough adapted to catch the coin dropping from the cylinder above it and to give the coin such direction as to fall upon and actuate the cylinder beneath 105 said trough, whereby the cylinders are given actuation consecutively by the fall and weight of one coin.

6. In a coin-operated mechanism, two or more oscillatory cylinders, in combination 110 with a coin-chute and one or more troughs, the mouths of which are placed above said cylinders, respectively, by means of which a coin dropped is left unrestricted in its lateral movements when dropping from each of said 115 chutes, and troughs upon the cylinder beneath and each trough adapted to catch the coin dropping from the cylinder above it and convey it to its mouth, whereby the directions of the movements given the cylinders 120 are unpredetermined and by chance.

7. In a coin-operated mechanism, the combination of a coin-chute and a series of oscillatory cylinders with recording devices for each movement of each cylinder, whereby the 125 movements of all the cylinders can be recorded.

8. In a coin-operated mechanism, a series of oscillatory cylinders carrying figures, in combination with a coin-chute and one or more troughs the mouths of which are placed above said cylinders, respectively, by means of which the coin is left unrestricted in its 130

lateral movements when dropping from each of said chutes, and troughs upon the cylinder beneath and each trough adapted to catch the coin dropping from the cylinder above it and 5 convey it to its mouth, whereby the movements given by the coin to each of the cylinders are unpredetermined and by chance and the several figures revealed by said cylinders when considered collectively will form chance 10 combinations.

9. In a coin-operated mechanism, an oscillatory cylinder free to turn in either direction, adapted to receive actuation from the fall and weight of a coin, in combination with 15 a coin-chute placed above and a receiving box located beneath said cylinder.

10. In a coin-operated mechanism, an oscillatory cylinder free to turn in either direction, adapted to be operated by the fall and 20 weight of a coin and a coin-chute placed above,

in combination with a partitioned box located beneath said cylinder.

11. In a coin-operated mechanism, an oscillatory cylinder, in combination with three coin-chutes placed, respectively, to the right 25 of, to the left of, and centrally above said cylinder, whereby a coin dropped through the coin-chute to the left falls upon and actuates the cylinder on that side, or if dropped through the coin-chute to the right falls upon 30 and actuates the cylinder on such side, or if dropped through the central coin-chute falls upon and actuates the cylinder in a direction unpredetermined and by chance.
